UNITED STATES PATENT OFFICE.

JAMES E. MCINTIRE, OF WEYMOUTH, MASSACHUSETTS, ASSIGNOR TO UNITED SHOE MACHINERY CORPORATION, OF PATERSON, NEW JERSEY, A CORPORATION OF NEW JERSEY.

MACHINE FOR INSERTING EYELETS.

Application filed November 20, 1919. Serial No. 339,364.

To all whom it may concern:

Be it known that I, JAMES E. MCINTIRE, a citizen of the United States, residing at Weymouth, in the county of Norfolk and 5 State of Massachusetts, have invented certain Improvements in Machines for Inserting Eyelets, of which the following description, in connection with the accompanying drawings, is a specification, like reference 10 characters on the drawings indicating like parts in the several figures.

This invention relates to fastener inserting machines and more especially to means for determining the desired initial positions 15 of the work relatively to the fastener-inserting mechanism. As the description of the invention proceeds it will be apparent that the latter is applicable to various fastener-inserting operations, but for purposes of 20 illustration the invention is exemplified herein with special reference to its use in the insertion of eyelets as by an eyeleting machine of the type disclosed in an application Serial No. 323,164, filed September 25 11, 1919, by Perley R. Glass.

In machines that act alternately to feed the work and to set one eyelet at a time it has been the practice, after setting the eyelets in one quarter of a shoe-upper, to fold the upper so as to place the two quarters in registration with each other, then prick a hole or otherwise form a mark on the other quarter by inserting a marking tool through the last eyelet of the first quarter, and then to set a series of eyelets in the other quarter beginning at the mark located as aforesaid and therefore at the opposite end of the quarter from that at which the eyeleting of the first quarter started, and 35 progressing therefrom. This practice requires considerable time in marking the second quarter, and the output of such machines has been restricted accordingly. Furthermore, the mark, at best, is relatively inconspicuous and more time is lost in placing the second quarter so that, in the judgment 40 of the operative, the first eyelet will be set accurately on the spot so marked.

In order to meet the difficulties peculiar 50 to the problems that arise in determining the initial positions of right and left quarters it has been proposed heretofore to provide eyelet-setting machines with reversi-

ble work-feeding mechanism by which the right-hand quarter will be fed in one direction and the left-hand quarter in the opposite direction. This proposition has not, however, found general use since it necessarily involves the sacrifice of advantages that make one-way feeding mechanism preferable. For example, when the feeding mechanism is reversible the punching, feeding and setting cannot be performed so advantageously, the mechanism is much more complicated, and the user is obliged to operate on 55 the right and left quarters according to a predetermined order or else to set the feeding mechanism according to whichever quarter is presented to it.

The foregoing conditions are mentioned 60 to show that the problem of gaging the initial positions of the quarters has been regarded as one of sufficient importance to warrant sacrificing other desirable features. In attaining the objects of the present invention it has been sought to retain, among 65 other desirable features, the advantages of utilizing the punch to feed the work, of feeding both quarters in the same direction, and of dispensing with the necessity for 70 marking the second quarter by the guidance of work already performed on the first quarter. So far as I am aware no eyeleting machine has ever been designed to reverse 75 the direction of the feeding motion without sacrificing the feeding function of the punch. On the other hand, no eyeleting machine has heretofore been provided that feeds both quarters in the same direction 80 without putting the user under the necessity of presenting the quarters according to a predetermined order and marking the second quarter by the work that has been performed on the first quarter. A somewhat 85 similar arrangement of gages has been proposed for certain hook-setting machines, but only by mounting the gages on a punching and feeding tool so that they encumber 90 the latter and, by their weight, impose additional load on the punching mechanism as well as on the feeding mechanism. This arrangement has disadvantages, two of which 95 are that the speed of the machine is retarded and the vibration increased.

An object of the present invention is 100 to provide improved means for locating the

quarters for the first eyelet of each. According to the illustrated embodiment of the invention this object is attained by providing two gages adjacent to the locality 5 where the eyelets are inserted into the work, said gages being arranged to indicate respectively the initial positions of certain inherently characteristic features of the work such, for example, as the leading 10 edges of the quarters respectively. To those familiar with the practices in the fitting-room of a shoe-factory, it is well known that the eyelet or lacing-hook at the upper end of a series should be relatively close to 15 the upper edge of the quarter whereas the eyelet at the lower end of the series should be more distant from the lower edge of the quarter in order to make allowance for the stock that is to be lapped with the vamp 20 where the quarters and vamp are afterward stitched together. Accordingly, when the lower edge of the quarter is the leading edge its initial position should be further advanced relatively to the eyelet-inserting 25 mechanism than the upper edge would be when the latter is the leading edge.

A feature of the invention consists in a device comprising two stationary gaging elements arranged to indicate, respectively, 30 more or less advanced positions from which the leading edges of the quarters should start when eyelets are about to be inserted.

Another feature of the invention consists in organizing the two said gages in such 35 manner that they may be adjusted, for example, relatively to each other, and collectively without disturbing their relation to each other. Such collective adjusting may involve motion in more than one direction. For example, according to the 40 construction shown these gages are adjustable collectively in lines parallel to the direction of feed and also in lines substantially transverse to the direction of feed. 45 In a machine of the kind shown the first of these collective adjustments is useful to maintain the desired relation between the gages and the work-feeding mechanism when the latter is altered to vary the length 50 of the feeding steps, and the second is useful to provide for varying the distance between the median line of the series of eyelets and the longitudinal edge of the work over which the lacing is to be passed.

55 Another object of the invention is to provide improved means for gaging the work to insure at all times the proper relation of the gages to each other and to the work whatever the length of the work-feeding 60 steps or the distance between the eyelets and the longitudinal edges of the quarters. According to the machine shown the work-feeding mechanism is provided with a regulator by which the length of the feeding 65 steps may be varied, and the illustrated

gaging device above mentioned is connected to the feed regulator in such manner that whenever the regulator is moved to alter the effective range of the feeding mechanism a corresponding adjusting movement 70 will be imparted automatically to the gages of that device to compensate for the variation in the feeding motion.

Eyeleting machines of various types, whether provided with a starting gage or 75 not, are usually provided with an edge-gage or guide arranged to contact with the longitudinal edge of the work relatively to which the line of eyelets is located, and, moreover, such guide is usually adjustable 80 transversely of the lines of feeding movement to vary the distance between the guiding edge of the work and the line of eyelets. Heretofore, in those machines that 85 include both an edge-guide and a starting gage, it has been common to make the two latter independent of each other so that no adjusting movement of one would affect the position of the other. I have found it to 90 be desirable, however, to adjust the starting gage or gages transversely of the lines of feeding movement whenever the edge 95 guide is so adjusted, in order to maintain uniform relation between the guiding edge of the work and the starting gage or gages, under all conditions. In accordance with this finding, therefore, I have provided, as 100 a feature of the invention, a new organization of the edge-guide and the starting gage or gages whereby the aforesaid uniform relation will be maintained when the edge-guide is adjusted transversely of the lines of feeding movement, and, according 105 to the organization shown, the transverse adjusting movement of the starting gages is imparted coincidently with the corresponding adjusting movement of the edge-guide. This not only avoids error in 110 respect to the relation of the elements concerned, but avoids additional means and an 115 additional adjusting operation for the starting gages, beyond those required for the edge-guide.

A further feature of the invention consists in arranging one or more of the gaging elements so as to bear upon a supporting surface other than that to which they are anchored, in order that they will be amply supported and protected against breakage or 120 accidental displacement.

Other features of the invention are illustrated by the drawings and are hereinafter described and claimed.

Referring to the drawings,

Fig. 1 represents a front elevation; partly 125 in section, of a portion of an eyeleting machine provided with gages constructed and arranged in accordance with the present invention;

Fig. 2 is a vertical section through the 130

structure intersected by line 2—2 of Fig. 1;

Fig. 3 is a perspective view including a presser-foot and punch-block and the gaging device in co-operative relation thereto, and including also a fragment of work such as the lower portion of the left-hand quarter of a shoe-upper;

Fig. 4 is a view of variable work-feeding mechanism with connections constructed and arranged to impart to the gaging device adjusting movement to compensate for feed-changing adjustment of the feeding mechanism;

Fig. 5 is a vertical section through the adjusting means intersected by line 5—5 of Fig. 2. See also line 5—5 of Fig. 6;

Fig. 6 is a vertical section through the structure intersected by line 6—6 of Fig. 5; and

Fig. 7 is a top plan view partly in section of means for adjusting the gages.

The description of the gaging device will be prefaced by a brief description of the work-feeding and eyelet-inserting mechanism included in the drawings. An eyelet-inserting tool is indicated at 10 and the usual spring-pressed spindle thereof is indicated at 11. These two elements are carried up and down by a plunger 12 arranged in fixed bearings in the frame of the machine. The delivery end of an eyelet-raceway is indicated at 13 and the eyelet indicated at 14 is supported thereby in position to be removed by the spindle 11 as the plunger 12 is depressed. It is to be understood that the raceway element 13 will be retracted from the path of the inserting tool in due time to clear the latter.

The clenching tool is indicated at 15 and is provided with a projecting central portion 16 that is utilized first to punch a hole in the work, then to feed the work, and finally to guide the barrel of the eyelet into the work. Fig. 1 shows the several elements in their initial positions, that is, their positions at the beginning of a cycle of operations. The specimen of work shown includes a left-hand quarter 17, an eyelet stay 18 and a lining 19. The work is supported by a raised portion 20 of a work-supporting plate 21. An opening 22 is formed in the portion 20 to receive the punch 16 and the upper end of the clenching tool 15. This tool is carried up and down by a plunger 23 and the latter is arranged to slide in a bearing afforded by a horizontally movable feed-carriage 24. The latter is arranged to slide on suitable guides one of which is indicated at 25. The punch stands initially out of line relatively to the inserting tool 10 and it describes the following motions:—First, an upward motion to punch a hole in the work conjointly with a punch-block 26, then a very slight downward motion sufficient to relieve the pressure against the punch-block,

then a lateral movement from right to left to feed the work and to locate the clenching tool in coaxial relation to the inserting tool, then a slight upward movement at the instant of clenching, and finally a return movement to the position shown in Fig. 1.

The punch-block 26 is rigidly connected to a plunger 27 and the latter is arranged to slide up and down in a bearing 28 afforded by a horizontally adjustable guide 29. This guide is arranged to slide on a fixed stud 30 projecting from a part of the machine frame. Although the plunger 27 is capable of being raised to facilitate the placing and the removal of the work it is sustained rigidly against the punching stress of the punch 16 when the machine is in operation, and at such times the lower face of the punch block 26 is either in contact with the upper surface of the work or is so close to the latter that there will not be any appreciable upward displacement of the work when the punch is functioning. The plunger 27 also carries a presser-foot 31 but the latter is movable relatively to the plunger and is normally depressed by a suitable spring (not shown) whereby downward pressure on the work is maintained continuously while the machine is feeding the work and setting the eyelets.

The extent to which the lower tool 15 is displaced laterally from the axis of the upper tool depends upon the length of feeding steps for which the work-feeding mechanism is adjusted, and since the gages hereinafter described are illustrated in connection with a machine of known construction having a variable work-feeding mechanism, the latter mechanism is illustrated herewith as a convenient means of showing how the gaging device may be incorporated into such a machine so as to derive adjusting movement from the feed-changing mechanism.

Referring to Fig. 4, the feeding motion is taken from a horizontally movable slide 35 that has reciprocatory motion of constant amplitude imparted to it by means such as a cam, not shown. The motion of the slide is transmitted through links 36 and 37 to an arm 38, the pivotal joint 39 by which the links are connected to each other being guided by a guiding link 40. Arm 38 is affixed to a rock-shaft 41 which has a bearing in the frame of the machine. An arm 42 is adjustably connected to the rock-shaft 41 and embraces a swiveled block 43 mounted on the feed-carriage 24. The amplitude of motion imparted to the feed-carriage is varied by shifting the fulcrum pin 44 about which the guiding link 40 swings. This fulcrum pin is carried by a regulating lever 45 that swings about the axis of stud 46. The handle of the regulator 45 overlies a stationary plate 47 in which holes 48 are formed for the reception of a

stop-pin 49. The handle is normally maintained against the stop-pin by a spring 50. Whenever the pin 49 is shifted from one hole to another the regulator 45 executes a motion that results in altering the effective feeding motion of the arm 42.

In order to effect a corresponding lateral adjustment of the punch-block and presser-foot whenever the feed-regulator is shifted 10 the mechanism includes suitable connections between the regulator and the slide 29. Still referring to Fig. 4, the regulator is provided with a cam-groove 51 which alters the position of a cam-roll 52 carried by a 15 lever 53. This lever is mounted upon but is movable relatively to the rock-shaft 41. The forward arm of the lever is connected to the slide 29 by a suitable universal joint connection that need not be described since 20 it is fully described in the aforesaid Glass application Serial No. 323,164. Thus, although the slide 29 does not move while the feed-carriage 24 is functioning it is shifted horizontally whenever the feeding mechanism 25 is altered to vary the length of the feeding steps, thereby maintaining the punch-block in the desired position for co-operating with the punch.

The gages by which the leading edge or 30 other characteristic feature of the work is located preliminarily to setting the machine in operation are indicated respectively at 55 and 56. The gage 55, according to the present design, is arranged to indicate the 35 initial position of the lower edge of a left-hand quarter, while gage 56 is arranged to indicate the initial position of the upper edge of a right-hand quarter. These gages as shown are adjustably connected to a 40 bracket 57, the latter being provided with grooves 58 through which the shanks of the gages extend. Adjusting screws 59 and 60 are rotatively mounted in the bracket as shown by Fig. 5 but they do not move 45 longitudinally in relation to the bracket. The shanks of the gages are bored and tapped for the reception of the adjusting screws so that when each screw is rotated the corresponding gage will be shifted in 50 lines substantially parallel to the direction in which the work is fed. Bracket 57 is connected to slide 29 so as to partake of 55 adjusting movement of the slide, the connection preferably providing for collective adjustment of the gages transversely of the lines of feeding motion. As shown, a pivot stud 61 forms the principal connection between the bracket and the slide while an 60 adjusting screw 62 forms other connection. 65 Screw 62 is mounted in ears 63 formed on the slide and although it is capable of being rotated it has no longitudinal motion relatively to the slide. An ear 64 formed on the bracket 57 is provided with an internal screw-thread arranged to co-operate

with screw 62 although the threaded part of the ear does not entirely surround the screw.

Bracket 57 is preferably provided with an abutment 65 arranged to bear against 70 the longitudinal edge 66 of the work to determine the distance between that edge and the row of eyelets. It is obvious that this distance may be altered by turning the screw 62 and it is also obvious that whenever such adjustment is made the gages 55 and 56 will partake of the adjusting movement and will therefore be maintained always in a predetermined relation to the edge 66 of the work.

The bottom surfaces of the bracket 57, work-guide 65, and gages 55, 56 are arranged to bear on the work-support 20 and on a surface 67 of the machine-frame. The adjustable elements are thus amply supported without imposing too great strain on the connections between the bracket 57 and the slide 29.

Having thus described my invention, what I claim as new and desire to secure by Letters Patent of the United States is:

1. In a fastener-inserting machine, the combination with work-feeding mechanism, of a stationary gage arranged to touch one edge of the work, and a stationary gage arranged to indicate a location for another characteristic feature of the work, said gages being adjustable collectively along lines parallel to the lines of feeding motion, and one of the gages being adjustable relatively to the other.

2. In a fastening-inserting machine, the combination with work-feeding mechanism, of a stationary gage arranged to locate one edge of the work relatively to said mechanism, and a stationary gage arranged to indicate a location for another characteristic feature of the work, said gages being constructed and arranged to be adjustable collectively along lines parallel to the lines of feeding motion.

3. In a fastener-inserting machine, the combination with punching means and work-feeding mechanism, of a gage arranged to guide one edge of the work relatively to the punching means, and a gage arranged to indicate a location for another characteristic feature of the work, said gages being constructed and arranged to be adjustable collectively along lines parallel to the lines of feeding motion, and one of them being adjustable relatively to the other.

4. In a fastener-inserting machine having work-feeding mechanism for feeding right and left quarters of a shoe-upper in the same direction, stationary adjustable means arranged to indicate the initial position for the right-hand quarter and stationary adjustable means arranged to indicate another initial position for the left-hand

quarter, and means for adjusting both of said indicating means by a single operation.

5. In a fastener-inserting machine having work-feeding mechanism including a combined punching and feeding tool, an adjustable unit comprising means arranged to guide an edge of the work and two stationary gages arranged to indicate respectively the initial position for the top of one quarter 10 and for the bottom of the other quarter of a shoe before said quarters are united with the vamp.

6. In a fastener-inserting machine having combined work-punching and work-feeding mechanism, an adjustable unit comprising stationary means arranged to indicate the initial position for a leading portion of the right-hand quarter of a shoe-upper and stationary means arranged to indicate another 20 initial position for a leading portion of the left-hand quarter.

7. In a fastener-inserting machine having work-feeding mechanism, stationary means arranged to indicate the initial position for 25 a leading portion of the right-hand quarter of a shoe-upper, stationary means arranged to indicate another initial position for a leading portion of the left-hand quarter, and means for adjusting both of said indicating means.

8. In a fastener-inserting machine having one-way work-feeding mechanism, stationary means arranged to indicate at one side of the setting locality the initial position 35 for a leading portion of the right-hand quarter of a shoe-upper, and stationary means arranged to indicate at the same said side of the setting locality another initial position for a leading portion of the left-hand quarter.

40 9. In a fastener-inserting machine having work-feeding mechanism, stationary means arranged to indicate the initial position for a leading portion of the right-hand quarter 45 of a shoe-upper, and stationary means arranged to indicate another initial position for a leading portion of the left-hand quarter, one of said means being adjustable relatively to the other, and means for adjusting both of them lengthwise of the path of feeding movement.

10. In a fastener-inserting machine having work-feeding mechanism, stationary means arranged to indicate the initial position 55 for a leading portion of the right-hand quarter of a shoe upper, and stationary means arranged to indicate another initial position for a leading portion of the left-hand quarter, one of said means being adjustable toward and from the other, and means for adjusting them in unison toward and from the setting locality.

60 11. In a machine for inserting fasteners in shoe upper quarters, work-feeding mechanism, means for guiding an edge of a quar-

ter during the work-feeding operation, a gage arranged to indicate the initial position for a leading portion of said quarter, and means arranged to adjust said guiding means and the gage in unison.

70 12. In a machine for inserting fasteners in shoe-upper quarters, fastener-inserting mechanism including a setting tool movable laterally to feed the work, regulatable mechanism for imparting feeding movement of 75 variant length to said tool, two gages for indicating the initial position of the leading portion of the right and left quarters respectively, a stationary structure to which said gages are attached, and means arranged to adjust said stationary structure so as to adjust said gages in unison according to the length of feeding movement.

80 13. In a machine for inserting fasteners in shoe-upper quarters, work-feeding mechanism, means for guiding an edge of a quarter during the work-feeding operation, a gage arranged to indicate the initial position for a leading portion of said quarter, means arranged to adjust said guiding means and the gage in unison in lines parallel to the direction of feeding motion, and means arranged to adjust one of them transversely of said lines.

85 14. In a machine for inserting fasteners in shoe-upper quarters, work-feeding mechanism, means for guiding an edge of a quarter during the work-feeding operation, a gage arranged to indicate the initial position for a leading portion of said quarter, means arranged to adjust said guiding means and the gage in unison in lines parallel to the direction of feeding motion, and means arranged to adjust them in unison in lines transverse to the lines of feeding motion.

90 15. In a machine for inserting fasteners in shoe-upper quarters, work-feeding mechanism, means for guiding an edge of a quarter during the work-feeding operation, a gage arranged to indicate the initial position for a leading portion of said quarter, means arranged to adjust said guiding means and the gage in unison, and means arranged to adjust one of them relatively to the other.

100 16. In a machine for inserting fasteners in shoe-upper quarters, work-feeding mechanism, means for guiding an edge of a quarter during the work-feeding operation, a gage arranged to indicate the initial position for a leading portion of said quarter, said gage being adjustable relatively to the guiding means in lines parallel to the lines of feeding motion, and means arranged to adjust said guiding means and said gage in 105 unison transversely of said lines.

110 17. In a machine for inserting fasteners in shoe-upper quarters, work-feeding mechanism, means for guiding an edge of a quarter during the work-feeding operation, a 115

gage arranged to indicate the initial position for a leading portion of said quarter, said gage being adjustable relatively to the guiding means, and means arranged to adjust said guiding means and said gage in unison.

18. In a machine for inserting fasteners in shoe-upper quarters, work-feeding mechanism, means for guiding an edge of a quarter during the work-feeding operation, a gage arranged to indicate the initial position for a leading portion of said quarter, said gage being adjustable relatively to the guiding means in lines parallel to the lines of feeding motion, and means arranged to adjust said guiding means and said gage in unison in lines parallel to the lines of feeding motion.

19. In a machine for inserting fasteners in shoe-upper quarters, work-feeding mechanism, means for guiding an edge of a quarter during the work-feeding operation, a gage arranged to indicate the initial position for a leading portion of said quarter, said gage being adjustable relatively to the guiding means in lines parallel to the lines of feeding motion, means arranged to adjust said guiding means and said gage in unison in lines parallel to the lines of feeding motion, and means arranged to adjust one of them transversely of said lines.

20. In a machine for inserting fasteners in shoe-upper quarters, work-feeding mechanism, means for guiding an edge of a quarter during the work-feeding operation, a gage arranged to indicate the initial position for a leading portion of said quarter, said gage being adjustable relatively to the guiding means in lines parallel to the lines of feeding motion, means arranged to adjust said guiding means and said gage in unison in lines parallel to the lines of feeding motion, and means arranged to adjust them in unison transversely of said lines.

21. A fastener-inserting machine having, in combination, work-feeding mechanism for feeding right and left quarters of a shoe upper in the same direction, and a stationary adjustable unit comprising two gages arranged to indicate at one side of the setting locality two initial positions for the right and left quarters respectively.

22. A fastener-inserting machine having, in combination, a punching tool, mechanism for operating the latter to feed right and left quarters of a shoe-upper in the same direction, and two relatively adjustable gages supported otherwise than by said tool and arranged to indicate at one side of the setting locality two initial positions for the right and left quarters respectively.

23. A fastener-inserting machine having, in combination, work-feeding mechanism, and two gages supported otherwise than by an element of said mechanism and arranged

to indicate initial positions for the top and bottom edges of the right and left quarters, respectively, of a shoe upper.

24. A fastener-inserting machine having, in combination, a work support, work-feeding mechanism constructed and arranged to feed right and left quarters of a shoe-upper in the same direction on said work-support, and two gages maintained in the plane of the work and arranged to indicate respectively the starting position for the top edge of one quarter and the starting position of the bottom edge of the other quarter.

25. A fastener-inserting machine having, in combination, two stationary gages arranged to indicate initial positions for leading portions of right and left quarters, respectively, of a shoe upper, and mechanism for feeding the quarters, in turn, in the same direction.

26. A fastener-inserting machine having, in combination, work-feeding mechanism, two stationary gages adjustable longitudinally of the lines of feeding motion and arranged to indicate initial positions for leading portions of right and left quarters, respectively, of a shoe-upper and means arranged to adjust said gages collectively lengthwise of the path of feeding motion.

27. In a fastener-inserting machine having step-by-step work-feeding mechanism that is regulatable to change the length of the feeding steps, a stationary gage arranged to indicate an initial position for a leading portion of the work, and means operable by regulating action of said feeding mechanism to adjust said gage according to the length of feeding step determined by such regulating action.

28. In a fastener-inserting machine having regulatable work-feeding mechanism, two stationary gages arranged to indicate initial positions for predetermined portions of right and left quarters, respectively, of a shoe upper, and means operable by regulating action of said mechanism for adjusting said gages in unison.

29. In a machine of the character described, fastener-inserting mechanism, regulatable work-punching and feeding mechanism having a shiftable punching locality and a feeding motion of variable length, and a shiftable edge-gage controllably connected to said punching and feeding mechanism so as to remain uniformly adjacent to the punching locality as the latter is shifted.

30. In a fastener-inserting machine having work-feeding mechanism, an adjustable unit comprising a gage for indicating the initial position for a leading portion of the work and means for guiding an edge of the work during the feeding thereof.

In testimony whereof I have signed my name to this specification.

JAMES E. McINTIRE.
